Patented Oct. 25, 1921.

Inventor
THOMAS G. HITT.

By his Attorney,
Mason Fairwick Lawrence.

UNITED STATES PATENT OFFICE.

THOMAS G. HITT, OF SEATTLE, WASHINGTON.

AERIAL TOY PROJECTILE.

1,394,551.

Specification of Letters Patent. Patented Oct. 25, 1921.

Application filed March 24, 1920. Serial No. 368,376.

To all whom it may concern:

Be it known I, THOMAS G. HITT, a citizen of the United States, residing at Seattle, in the county of King and State of Washington, 5 have invented certain new and useful Improvements in Aerial Toy Projectiles; and I do hereby declare the following to be a full, clear, and exact description of the invention, such as will enable others skilled in the art to 10 which it appertains to make and use the same.

This invention relates to amusement devices and particularly to aerial projectiles for use in connection with explosive fireworks.

The objects of the invention are to provide 15 a simple and easily constructed article which may be sold at a low cost and so be within the reach of the average American boy's pocket book on the fourth of July, and other occasions when fireworks are used, which 20 article will produce a large amount of pleasure at limited expense, and be capable of repeated use in connection with fire-crackers and other explosive materials.

A further object is to provide an aerial 25 projectile with varied colors, preferably red, white and blue, which may be easily thrown into the air a considerable height by a small amount of explosive material.

A still further object is to provide an attractive projectile with a hollowed base, 30 which may be placed over a lighted fire-cracker of suitable size, and which by the explosion of the fire-cracker, will be thrown into the air, for amusement purposes.

With these and other objects in view, the 35 invention consists in the novel features and construction, the combination and arrangement of parts hereinafter more fully set forth, pointed out in the claim and shown 40 in the accompanying drawings, in which—

Figure 1 illustrates a side elevation of the projectile.

Fig. 2 illustrates a similar view in section, and

Fig. 3 illustrates a view of the base of the projectile.

Like numerals on the different figures represent like parts.

Numeral 1 is the side wall of a short round cylinder, with an open base and within the 50 walls, as 2, and the top of the cylinder is closed with disk 3, of any suitable material, preferably of wood, and above the disk 3 is a cap 4 which is made in the form of a cone with a sharp point 5 at the extremity, 55 for the purposes herein mentioned.

The cylindrical walls are preferably made from thick card board, capable of withstanding considerable rough usage, yet not sufficiently heavy to prevent the device being 60 thrown upward without great exertion or force. The walls of the cap portion are preferably made of thinner and lighter material than that used for the cylinder and may be constructed of thin card board. 65

For attractiveness, I prefer to cover the walls of the cylinder and cap with colored paper, such as red 6, white 7, and blue 8.

In use, the cylinder is placed over a lighted fire-cracker or other suitable charge of explosive lying on the floor or street, thus the base of the wall will be closed by the body upon which the explosive rests, until the explosion occurs, whereupon the projectile will be thrown upward by the concussion a considerable distance, the light cap piercing the air, and the heavier walls of the cylinder and the disk steadyng the flight of the toy. On its return to earth, it may be again used for any number of times in the same manner. 75

What I claim is:

In an aerial toy projectile, a hollow cylinder with one end open and adapted to be rested upon a flat surface, a wall disk closing the other end of the cylinder, a hollow cone shaped cap formed integral with the cylinder and surmounting the disk, said cap terminating at its outer end into a sharp point. 85

In testimony whereof I affix my signature.

THOMAS G. HITT.
